UNITED STATES PATENT OFFICE.

KATHERINE L. WELSH, OF OMAHA, NEBRASKA.

SUPPORT FOR FLAT-IRONS.

1,322,853.

Specification of Letters Patent. Patented Nov. 25, 1919.

Application filed February 25, 1919. Serial No. 279,140.

To all whom it may concern:

Be it known that I, KATHERINE L. WELSH, a citizen of the United States of America, residing at Omaha, in the county of Douglas and State of Nebraska, have invented certain new and useful Improvements in Supports for Flat-Irons, of which the following is a specification, reference being had therein to the accompanying drawing.

10 The invention relates to supports and has for its object to provide a support, whereby an electric flatiron may be supported in an inverted position so that the bottom thereof may be used for heating water or cooking 15 by placing thereon a receptacle in which the water or article to be cooked is placed.

A further object is to provide a support for an electric iron wherein the uprights, which support the flatiron are of maximum width 20 which may pass through the handle of the flatiron and to provide the portion of the support that flatiron rests on with a concave portion, which conforms to the convex curvature of the top of the flatiron thereby 25 preventing rocking of the flatiron when in place on the support, also to provide the concave portion of the support with notches for the reception of the arms of the handle at a point where they are nearest to each 30 other, the notches additionally preventing rocking displacement of the flatiron when in use.

With the above and other objects in view the invention resides in the combination and 35 arrangement of parts as hereinafter set forth, shown in the drawings, described and claimed, it being understood that changes in the precise embodiment of the invention may be made within the scope of what is 40 claimed, without departing from the spirit of the invention.

In the drawings:—

Figure 1 is a perspective view of the support, showing a flatiron in position thereon. 45 Fig. 2 is a front elevation of the support, showing the flatiron in position thereon.

Fig. 3 is a sectional view taken on line 3—3 of Fig. 2, showing the flatiron in elevation thereon.

50 Referring to the drawings the numeral 1 designates the support and 2 a flatiron in position thereon. The support is preferably formed from one piece of metal and comprises the concave body portion 3. Bent 55 downwardly as at 4, from the body portion

are supporting legs 5, which are adapted to rest upon a table or the like and support the body portion spaced from the same.

The edges of the body portion 3 taper inwardly as at 6 and the body portion 3, at a point centrally thereof, is provided with oppositely arranged notches 7 for the reception of the arms 8 of the handle 9 of the flatiron, said arms 8 engaging the notches at a point adjacent the body of the flatiron and therefore where the arms are closest together. It will be seen that with the arms of the handle 9 in engagement with the notches that it will be impossible for the flatiron to rock on the support, or become 65 displaced thereon and it will also be seen that this rocking or displacement of the flatiron will be additionally prevented by the fact that the concave body portion of the support is of the same curvature as the upper surface of the flatiron.

When it is desired to place the flatiron in position on the support, one of the supporting legs 5 is passed through the handle at the points 10, which is the point where they 80 are farthest apart. The iron is passed up and over the concave body portion until the arms 8, of the handle 9 are in position so that they will be received by the notches 7, when the convex portion 11 is allowed to 85 rest upon the concave body portion of the support.

The invention having been set forth, what is claimed as new and useful is:

1. A support for flatirons comprising a body portion for supporting an iron in inverted position, said body portion being narrower substantially centrally than at its ends and downwardly extending legs at the ends of the body portion for supporting the body portion spaced above the article on which it rests.

2. A flatiron support comprising a concave body portion supported spaced from the article on which it is placed, said concave body portion being narrower at its central point and provided with oppositely disposed notches at said narrow point, said notches being adapted to receive the arms of the handle at a point adjacent where they 105 join the body portion of the flatiron and are nearest together, thereby preventing rocking of the flatiron on the body portion of the support, said concave body portion being of the same curvature as the convex top of the 110

body of the flatiron, thereby additionally assuring a steady holding of the flatiron in position when in use.

3. A support for flatirons comprising a body portion for supporting an iron in inverted position, said body portion being provided with opposite notches substantially centrally of the body portion for the reception of the handle of the iron adjacent the

body thereof and downwardly extending legs at the ends of the body portion for supporting the body portion spaced from the article on which its support as a whole rests.

In testimony whereof I hereunto affix my signature.

KATHERINE L. WELSH.
